METHOD AND APPARATUS FOR PUMPING A VOLATILE LIQUID

William F. Mesinger, Mount Vernon, N. Y., assignor, by mesne assignments, to Union Carbide and Carbon Corporation, a corporation of New York

Application July 18, 1941, Serial No. 402,891

34 Claims. (Cl. 103—153)

1

This invention relates to a method and apparatus for pumping a volatile liquid, and particularly to the pumping of a liquid which has its boiling point temperature at atmospheric pressure materially below 273° K., such as liquid oxygen.

The invention has for its object generally the provision of a combination of improved pumping steps, together with suitable apparatus for effecting the same, whereby a highly volatile liquid may be positively pumped by a reciprocating type pump, particularly one having a plunger, against relatively high heads of pressure.

More specifically, the invention has for its object the provision of a novel cycle of pumping steps whereby the material in the liquid phase may be positively displaced and any material vaporized in the pump is readily removed, together with suitable plunger pumping apparatus and auxiliaries therefor, whereby the several pumping steps of the invention are carried out.

Another object of the invention is to provide an arrangement of apparatus for pumping a liquefied gas of the character indicated with a plunger type pump having adequate clearances and liquid inlets and outlets so arranged that displacement of the liquid by opposite movements of the piston and liquid is effected. In addition to the peripheral clearance about the plunger characteristic of plunger type pumps, there will necessarily be a small clearance at the end of the discharge stroke.

Another object of the invention is to provide a pump construction having the clearances consistent with said opposite movements, with means for compensating for such clearances and for nearly completely offsetting the inefficiency otherwise incident to the presence of vaporized gas material that would tend to occupy such clearances.

Another object is to provide a pump of the character indicated with a plunger arranged for conducting relatively little heat from the outside atmosphere to the liquid being pumped.

Another object is to provide a plunger type pump with an improved packing that is heated so as to operate under substantially optimum packing conditions when pumping a relatively cold liquid such as liquid oxygen.

Another object is to provide a plunger type pump with an auxiliary gas pump for removing any gas phase generated internally that would otherwise tend to reduce the pumping efficiency of the pump, or permit the same to become gas-bound.

2

Still another object of the invention is to provide a suitable arrangement for positively operating and timing the valves in a plunger type pump whereby the inflow of liquid phase material is properly controlled and coordinated with the movement of gas phase material in the interior of the pump during the pumping cycle.

Other objects of the invention will in part be obvious and will in part appear hereinafter.

The invention accordingly comprises the several steps and the relation of one or more of such steps with respect to each of the others, and the apparatus embodying features of construction, combinations of elements and arrangement of parts which are adapted to effect such steps, all as exemplified in the following detailed disclosure, and the scope of the invention will be indicated in the claims.

For a fuller understanding of the nature and objects of the invention reference should be had to the following detailed description taken in connection with the accompanying drawing, in which:

Fig. 1 is a view, mainly in side elevation, showing schematically a pump arranged for pumping a volatile liquid in accordance with the invention;

Fig. 2 is an enlarged vertical sectional view of the pump shown in Fig. 1, parts being shown in elevation, constructed in accordance with the invention;

Fig. 3 is a sectional view, taken on the line 3—3 in Fig. 2;

Fig. 4 is an enlarged sectional view showing details of a valve device employed in the present invention; and

Fig. 5 is a fragmentary view, partly in section and partly in elevation, showing a modification.

In the practice of the present invention two major steps are employed in association with a pump having a plunger provided with a clearance space thereabout. The first step operates to draw liquid from a source of supply into the pump chamber; the second effects the discharge of liquid by positive displacement thereof, the effects of gas binding being minimized by providing for a counter-movement of liquid and piston upon the discharge.

When the liquid entering the pump is of only slightly lower temperature than the plunger so that heat exchange and vaporization result and suction by the plunger may not be depended upon to draw in a charge of liquid, a suitable pressure feed is provided, such as may be had by a gravity feed of the liquid to the pump cylinder, as shown, to minimize the vaporization. The gas

thus generated is positively removed subsequently by the employment of an auxiliary gas pump, such removal being accomplished during the short interval transpiring while the suction stroke is being completed. The pump cylinder is at the same time cooled by permitting ebullition of liquid in a surrounding jacket. Heat is thus removed from the parts of the pump while gas is at the same time generated.

Upon the beginning of the discharge stroke, pressure begins to rise in the pump chamber of the pump until a value is attained sufficient to open a discharge valve that is normally biased closed. This event may be hastened by momentarily admitting gas at a relatively high pressure into the clearance space at the beginning of the discharge stroke, which operates to offset the effect of such clearance. Liquid is thus positively discharged at a relatively high pressure during the balance of the discharge stroke.

A pumping apparatus constructed to carry out the steps of the invention consists of a pumping chamber or cylinder in which reciprocates a diametrically smaller plunger which is preferably hollow to reduce the mass of metal and filled with suitable insulation in order to provide support for its walls. Connected to the cylinder are liquid supply and discharge conduits having suitable valves for controlling the inlet to and outlet from the cylinder. Preferably three mechanically operated suction stroke valves are provided, one at the bottom and two at or near the upper portion of the cylinder; the valve at the bottom being arranged to allow liquid to run into the cylinder while the upper two vent any gas back to the source of liquid supply, such as a liquid oxygen storage container. A suitable auxiliary or gas pump, which may be of a bellows type, is inserted in the vapor line to achieve the positive removal of the gas from the pump cylinder during the suction stroke and put it back at the beginning of the discharge stroke in order to supercharge the pump. During the discharge stroke, liquid is forced out through a suitably biased outlet valve, for example, a gravity controlled valve, to the discharge line. An auxiliary vessel or chamber is preferably located near the cylinder and arranged to serve as a gas phase receiver at the discharge pressure. Such receiver is connected to the pump cylinder through a valve which is mechanically operated and opened momentarily to receive gas material from the cylinder at the end of the discharge stroke in order to reduce the pressure of the gas remaining in the clearance space before a suction stroke begins and is again opened for a moment to discharge back the received gas material under pressure to the cylinder. The opening at the beginning of the discharge stroke is seen to minimize the effect of the plunger clearance space and further to supercharge the pump cylinder. A fore-chamber is provided and maintained at a relatively low pressure and preferably surrounds the pump cylinder and is kept full of liquid drawn from the storage container in order to assist in keeping the pump cylinder cold. The discharge conduit is preferably disposed in heat conducting relation with the pump cylinder at a point between the lower portion and a plunger packing sleeve, in order to keep it cool, thus preventing excessive transfer of heat from the packing end toward the pump cylinder. The top portion of the packing sleeve is also advantageously provided with a suitable

heating means, such as an electric heater, in order that it may be maintained at a temperature consistent with good packing operation.

Referring now to the drawing, and particularly to Fig. 1, a storage container is shown at 10, which is of a character adapted to hold a supply of the liquefied gas to be pumped to receiving or consuming apparatus (not shown in the drawing in the interests of clearness of illustration). From the bottom of the container 10, a liquid supply line 11 is diagrammatically indicated as leading to the inlet of a plunger pump, here denoted generally by 15. Such pump has a casing 150 and is provided with a gas phase equalizing connection 12 leading to the gas space of the container 10. A liquid phase discharge connection 13 leads from the outlet of the pump; container 10 being shown as also having a filling connection 14.

The pump 15 may have any convenient location with respect to the container 10 but is here shown, by way of illustration, mounted with its casing on a floor or ground and having its inlet at a level a little below the bottom of the container, in order to provide the desired pressure at the inlet.

Details of an exemplary construction for pump 15 are shown in Fig. 2. Here a plunger 20 is provided that is hollow and closed at the bottom and has a filling of insulation at 200 (see Fig. 3).

The insulating filling at 200 can, of course, be omitted if the plunger wall is made strong enough to be entirely self-supporting. However, by providing an insulating filling for the plunger, which is both mechanically strong and a relatively poor conductor of heat, the metal wall of the plunger 20 can be made quite thin and the heat storage capacity and conductivity of the plunger may then be correspondingly reduced. The heat storage capacity is an appreciable factor because the plunger absorbs some heat in its upper position, and the smaller its heat capacity the smaller will be the amount of heat carried to the pump cylinder when the plunger is in the lower position. Such plunger is arranged to pass downwardly into a pump chamber 210 through a sleeve 21 which has a packing 22 associated therewith. The pump chamber 210 is formed as the bore of a pump cylinder which may be provided either as a single member, or as a plurality of associated members. A plurality of members is here shown in the drawing, by way of example, since it facilitates manufacture.

Accordingly, an upper member 23 is provided which has its upper portion reduced to provide sleeve 21, the exterior of which has a thread at 21' by which nuts and other parts are held in place, as hereinafter explained. To member 23 is attached a lower member 24 which continues the bore 210 comprising the portion of chamber in which the plunger 20 works. This lower portion may be appropriately referred to as the working barrel portion. The diameter of the bore is made sufficiently greater than that of the plunger to provide the desired clearance space about the plunger. This clearance space may be varied somewhat depending upon the inner diameter of the cylinder and the speed of operation of the plunger. In general it should be small but sufficient to permit the counter-flow of the liquid past the plunger during the discharge stroke without subjecting the liquid to an excessive speed of flow such as to cause fric-

tional heating. The lower end of member 24 is closed by a base member 25 which may be threadedly attached to member 24, and is preferably counterbored, as shown at 250, and has a plurality of passages, as at 251 and 252, leading thereto. The base member 25, which thus serves to support the members 23 and 24, preferably has a central boss 25' or upstanding portion formed about the counterbore or depression 250 and serves as a support for a wall 26 of a jacket chamber 260; such wall being cylindrical and of greater diameter than that of the inner or lower member 24. By this means, wall 26 is held in spaced relation to the member 24 between the base member 25 and the upper member 23; the latter preferably having a depending boss 23' of the same diameter as boss 25' and of a character adapted to be received in the upper end of wall 26. By this means the intervening space is seen to be annularly formed and adapted for cooling the pump chamber 210. The base member 25 thus serves to close at the bottom not only the pump chamber but also the jacket chamber. The jacket chamber 260 is made to serve as a fore-chamber to the pump chamber 210 by providing the jacket wall 26 with a nipple 211 at one side, to which the liquid inlet connection 11 is attached; there being also another passage 212 in base member 25 which connects chamber 260 to passage 252.

A valve is provided in these connections to control the inlet of liquid to the pump chamber 210. Accordingly, the inner end of passage 252 is reduced as at 253 to provide a shoulder 254 upon which seats a valve 255 that is on a stem 256. This latter is slidably mounted in a sleeve 257 that has a packing 258 retained by a gland or nut 259; the sleeve being shown as having threaded engagement with the outer end of passage 252. The stem 256 projects to the exterior of the pump and has actuating force applied as hereinafter described. An enlarged view of this construction is shown in Fig. 4, where it is seen that the stem 256 has a sleeve coupling 264 connecting it to a cam follower 266 which is actuated by a cam 265. By such arrangement, it is seen that when the opening of the valve 255 is synchronized with the upward or suction stroke of plunger 20, liquid flows into the pump chamber 210 from the storage container 10.

The jacket or fore-chamber 260 is preferably vented to the gas space of the storage container, in order that the liquid therein may be in pressure equilibrium with the contents of the storage container and moved under the influence of a uniform force, here the force of gravity, first into the fore-chamber 260 and from the fore-chamber into the pump chamber 210 when a suction stroke takes place. To accomplish such venting, the lower portion of member 23 is provided with passages 231 and 232 leading from the upper part of chamber 260 to a point at which connection 12, that communicates with the container gas space, is attached. The inlet end of passage 231 is preferably provided with a float valve 235 in a cage 233, in order to prevent the entry of liquid, such cage having gas passages at 234. This valve is of a suitable construction and relative weight such that it will normally float on the liquid, but will have sufficiently greater weight than an equal volume of the gas, such that, when suspended in gas only, it will overcome a substantial amount of differential gas pressure and drop down.

Venting passage 232 is traversed by a passage

236, the lower portion 236' of which is threaded for the reception of a threaded sleeve 247 of a packless valve 245 which has an actuating stem 246 to which is attached a metallic bellows 248 anchored in a removable cap or nut 249 of the sleeve. Valve 245 seats on a valve opening provided at the juncture of the upper portion of passage 236 with that of 232.

When valve 245 is open, it establishes communication through the upper portion of passage 236 between passages 231-232 and additional gas escape passages 241-242 which communicate with pump chamber 210 at a point a little below the upper end of the stroke of plunger 20. Passage 241 is reduced and provides a shoulder at its juncture with passage 242 upon which seats a valve 245' which is similar but preferably of enlarged form relative to that at 245. Valve 245' is shown as of the packless type and has an actuating stem 246' in a sleeve closed by a cap or nut 249.

Passage 242 also has communicating with it a passage 243 leading to a chamber 244 in which works a piston for the gas pump which is arranged to be actuated in synchronism with the strokes of plunger 20.

The passages 231-232, 241-242, together with that at 243 and chamber 244, are preferably provided as bores in a portion of member 23 which is enlarged to accommodate the same, such enlargement being shown at 23x; a cross-section of the same along a broken line appearing in Fig. 3. Here it is seen that at a point a little above the inner end of passage 241 another set of passages is provided. This other set comprises horizontal passage 271 that is connected by vertical passage 272 to a third passage 273 which communicates with discharge connection 13, this latter including a coiled portion 123 that is disposed about the neck of upper portion 23 below its threads 21'. At the juncture of passages 272 and 273 is a valve seat 274 on which seats by gravity a valve 275; the enlargement 23x preferably being formed with extensions of these passages which are closed with suitable plugs, in order that access may be readily had thereto for assembly and servicing.

The point at which passage 271 communicates with pump chamber 210 is substantially at the upper end of the plunger stroke. In order that the inner end of this passage may not be too restricted, an annular recess 276 is cut in the wall of the pump chamber, thereby giving relatively free access from all parts of the liquid at this height into the passage 271.

The passage 251 in the base member leads to a gas receiver or vessel 220 that has a connection 221 leading into an enlarged horizontal portion 222 which joins passage 251 and provides a shoulder on which a valve 255' seats. Valve 255' is preferably similar to that at 255 and has an actuating stem 256' sliding in a sleeve 257' that engages threadedly with the outer end of passage 222.

65 The gas pump chamber 244 may have any convenient construction. The arrangement for such here shown comprises a recess in the upper face of the enlargement 23x, which recess is internally threaded for the reception of a cylindrical member 27, the upper end of which is closed by a perforated cap 28 through which piston rod 29 protrudes. Rod 29 is arranged to actuate a bellows 30 which serves as a piston in chamber 244, the bellows being anchored at its upper end to the interior of cap 28, the lower end of the bellows

being closed by the rod attaching means employed. By such arrangement the gas pump is adapted for removing gas from the pump chamber 210, the chamber 244 having direct communication with the pump chamber through passages 241—242—243 when the valve 245' is open. Accordingly, it is desired that rod 29 shall be actuated in synchronism with plunger 20 but not in phase with it.

The passages 241—242, which communicate with passage 232, provide means for venting the gas withdrawn by the gas pump by way of passage 236, valve 245 and connection 12; the valve 245 being controlled by a cam, as hereinafter described; such cam being a part of the train of mechanism which also actuates valves 245', 255, and bellows 30.

The packing space in sleeve 21 is here provided by counterboring the bore 210 a desired distance to form a cylindrical chamber into which packing, in the form of a plurality of packing rings 22, is introduced and held in place by a gland follower 32 and packing nut 33. The packing rings 22 are made of a suitable material, which is inert to oxygen, such as asbestos fibers, and the packing also incorporates a non-combustible lubricant, such as flake graphite, or a non-oxidizable liquid, such as tricresyl phosphate or the like.

About the threaded upper end of sleeve 21 are also disposed lock nuts 34, between which and the nut 33, is preferably disposed a heater 35 comprising a jacket of insulating material and an electrical resistance coil 36 embedded therein. Such heater is energized when desired from a suitable source of current, for example, from bus-bars, as shown at 37.

In order to actuate the plunger 20, the rod 29 of the gas pump, and the several valves in the proper sequence to carry out the steps of the invention, prime moving means properly correlated and mechanically coupled for actuating these parts, are provided. While any suitable prime mover, of course, may be employed, that shown in the drawing by way of example comprises a single electric motor M (see Fig. 1). Such motor is connected to drive a gear or pulley 40 that is mechanically coupled by a suitable train with the other parts. Motor M is here shown as driving pulley 40 by means of a belt; the pulley having a crank 41 and attached connecting rod 42 connected to actuate one end of a walking beam 43. This latter is fulcrumed or pivotally mounted on the upper portion of casing 150 by a rocking link 44; the other end 45 of the walking beam being pivotally connected to plunger 20.

Pulley 40 is arranged to drive or mesh with a gear 50 on a cam shaft 51 that is so geared as to rotate with a suitable speed relative to the pulley 40. Shaft 51 passes into and is journaled in easing 150, and is geared to drive another cam shaft 52 that is vertically disposed and also journaled in easing 150. Shaft 51 carries a cam 53 which has a protrusion or other formation on its face for engaging with a follower 55 that is on the stem 256' of valve 255' for actuating the same. Shaft 52 carries cam 265 at its lower end inside the follower 266 and has three additional cams, namely, those actuating followers at 46 and 56 and cam 65. Follower 46 has a link 47 connecting it to one arm of a bell crank lever 48 which has its other arm connected to the valve stem 246 for actuating valve 245. Follower 56 is coupled to stem 246' for actuating valve 245'.

Cam 65 is advantageously a drum type of cam with a sinuous groove cut in its cylindrical sur-

face, in order to actuate positively in both directions the gas pump through a following lever 66 pivotally mounted on the casing 150 with one arm connected to rod 29, while the other works in the cam groove.

In operation, the pump of the present invention is set in motion by starting the motor M and admitting liquid phase, for example, by opening the controlling valve in conduit 11. The packing heater 35 is also preferably started at the same time.

From the arrangement described, it is seen that, when the pulley 40 rotates, the plunger 20 is reciprocated through the linkage 41—42—43 and the cam shafts 51 and 52 rotated together with their several cams which are, of course, adjusted to have the desired phase relationship. When plunger 20 is moved by pulley 40 from the bottom of chamber 210 to the top a suction stroke takes place.

At the beginning of the suction stroke, the valves 245, 245' and 255 are opened. A re-expansion of the gas remaining in the pump chamber 210 is thus allowed to take place through valves 245 and 245' back to the gas space of the liquid storage container. At the same time, the piston 30 of the gas pump is pulled up thereby drawing into the cylinder 27 a charge of gas. This collapses the bellows 30 and materially contributes to the positive displacement of the gas from the pump chamber 210, depending upon the relative capacity of the pump chamber 210 to that of the gas pump. It is seen, in consequence, that liquid rises substantially to the opening of passage 241 when the suction stroke is completed. The plunger 20 dwells at the upper end of its stroke for a short period due to the crank movement through dead center position and during this dwell period supercharging takes place. Valves 255 and 245 now close, and the bellows 30 of the gas pump is quickly and full distended, forcing the gas charge therein into the clearance space about plunger 20 in the upper portion of pump chamber 210. This gives an almost instantaneous supercharging effect. After the bellows 30 has become fully distended, and with plunger 20 still near the top of its stroke, valve 245' is closed. At this same instant valve 255' is opened to admit more gas from the vessel or chamber 220, where it has been retained under a higher pressure, into the pump chamber 210 below plunger 20, the gas passing into the liquid which partly condenses it. This valve 255' remains open for only a short period of time and closes at or before the instant when the plunger contacts the liquid in chamber 210. Thus the gas pump furnishes the first stage of supercharging, and vessel 220 through valve 255' furnishes the second stage.

As plunger 20 contacts the liquid in chamber 210, some gas is generated and the parts are cooled. Compression of the gas ensues, and liquid rises and finds exit past valve 275. As plunger 20 reaches the bottom of chamber 210 and the discharge stroke is completed, valve 255' opens again momentarily and allows in part a re-expansion of the residual gas in chamber 210 to drive liquid and gas from the clearance space into vessel 220, after which valve 255' closes again. The material thus accumulated in vessel 220 under pressure is, of course, used in the next cycle to supercharge the chamber 210, as described above. At this point, a new cycle begins with the rising of plunger 20 and the simultaneous opening of valves 255, 245, and 245'.

The movements of the plunger 20, the rod 29, and the valves are seen to be effected in proper sequence by the crank and gearing actuated by the motor M.

In the modified form of the invention shown in Fig. 5, the bellows type gas pump is dispensed with, also the connection of the gas escape passages back to the gas space of the storage container. In the modified form, a rotary type of gas pump is employed and auxiliary gas receivers are associated therewith in order to receive and store gas phase for release under pressure to effect the first stage of supercharging.

Here a passage 281 is arranged to lead off gas into a passage 282 which has a third passage 283 leading thereto and controlled by a valve 245" which functions as does that at 245 in Fig. 2. At the junction of passages 281 and 282 there is a shoulder upon which seats a valve 285 that is arranged to be cam actuated in substantially the same manner as, and is similar in construction to, that at 255. Hence it is shown having its stem passed to the exterior through a threaded sleeve 287. Escape of gas from passage 282 is provided by way of a connection 288 which communicates at its inner end with passage 282 and leads to a receiver or vessel 290 and to a rotary type gas pump 300. Gas pump 300 is advantageously driven by means of an independent prime mover, such as motor M, the receiver 290 being connected to the line at 288 by a branch connection.

To provide for introduction of the withdrawn gas when under pressure, a passage 291 is arranged to lead into plunger bore 210 at a point substantially opposite passage 271 which leads off the discharged liquid. Passage 291 leads from a second passage 292 that has a third passage 293 leading thereto from a connection 299 leading from the discharge side of pump 300. At the juncture of passage 291 with passage 292 is another shoulder which provides a seat for a valve 295 that has a stem in a sleeve 297 passing to the outside of the pump for receiving actuating force. Valve 295 is preferably of the same form and type as valves 285 and 255.

Gas pump 300 and its motor M are arranged for continuous performance and another receiver or vessel 310 is provided on the discharge side of the pump and floatingly connected to the connection 299, as indicated.

In operation, this second form of the invention is seen to have valves which are operated in proper sequence by cams, as in the first modification. The gas entering connection 288, when either valve 245" or 285 is open, first passes into receiver 290, as the volume of such gas is generally greater than the capacity of pump 300 to receive momentarily. The pump 300, by its continued operation, gradually draws out the gas from receiver 290 when valves 245" and 285 are closed and compresses it and discharges it at a relatively high pressure into the connection 299. The receiver 310 receives and stores this gas until the valve 295 opens when a charge of gas for supercharging purposes is admitted therefrom into chamber 210. It is contemplated that this charge may subsequently be supplemented in the cycle by a charge from vessel 220, as above described.

The forms of Figs. 2 and 5 are each described as being provided with two supercharging means, but it will be understood that dependent upon circumstances or conditions of operation one or the other of these two means may be omitted. It will be apparent also that there are disclosed features of construction and principles of opera-

tion which are capable of utilization to advantage without incorporation therein of either supercharging means.

Since certain changes in carrying out the above method and in the constructions set forth, which embody the invention, may be made without departing from its scope, it is intended that all matter contained in the above description or shown in the accompanying drawing shall be interpreted as illustrative and not in a limiting sense.

Having described my invention, what I claim as new and desire to secure by Letters Patent is:

1. Apparatus for pumping a volatile liquid having a boiling point temperature materially less than 273° K. at atmospheric pressure, comprising the combination with a device for supplying liquid to be pumped having therein spaces for both gas and liquid, of a pump having a pump chamber in communication respectively with said gas and liquid spaces, valve means for closing said communication, a liquid discharge for said pump chamber, a plunger arranged to work in said pump chamber, the latter being provided with a desired clearance and said plunger being adapted to displace liquid through said discharge, means for supercharging the clearance space in said pump chamber by the addition of material being pumped at a pressure higher than the normal inlet pressure, and correlated means for actuating said plunger, said valve means and said supercharging means.

2. Apparatus for pumping a volatile liquid having a boiling point temperature materially less than 273° K. at atmospheric pressure, comprising the combination with a container for supplying liquid to be pumped, of a pump having a pump chamber and a fore chamber surrounding the pump chamber connected to said container and arranged to maintain therein a supply of the material being pumped, valve means for controlling the admission of liquid to said pump chamber from said fore chamber, a liquid discharge for said pump chamber, a plunger arranged to work in said pump chamber, the latter being provided with a desired clearance and said plunger being adapted to displace liquid through said discharge by the counter-movement of liquid and plunger, and correlated means for actuating said plunger and said valve means.

3. Apparatus for pumping a volatile liquid having a boiling point temperature materially less than 273° K. at atmospheric pressure, comprising the combination of a pump chamber, valve means for controlling the admission of liquid to said pump chamber, a liquid discharge for said pump chamber, a plunger arranged to work in said pump chamber, the latter being provided with a desired clearance and said plunger being adapted to displace liquid through said discharge, means for supercharging the clearance space in said pump chamber by the addition of material being pumped at a pressure above the normal inlet pressure and provided with valve means controlling communication with said pump chamber, and correlated means for actuating said plunger and said last mentioned valve means.

4. Apparatus for pumping a volatile liquid having a boiling point temperature materially less than 273° K. at atmospheric pressure, comprising the combination with a container for supplying liquid to be pumped, of a pump having a pump chamber and a surrounding fore chamber connected to said container and to said pump chamber, valve means for controlling the ad-

mission of liquid to said pump chamber through said fore chamber, a second valve means for controlling the venting of gas from said pump chamber, a liquid discharge for said pump chamber, a plunger arranged to work in said pump chamber, the latter being provided with a desired clearance and said plunger being adapted to displace liquid through said discharge by the counter-movement of liquid and plunger, means for supercharging the clearance space in said pump chamber, a third valve means controlling communication between said supercharging means and said pump chamber, and means for actuating said plunger and all of said valve means.

5. Apparatus for pumping a volatile liquid having a boiling point temperature materially less than 273° K. at atmospheric pressure, comprising the combination of a pump having a pump chamber, valve means for controlling the admission of liquid to said pump chamber, a second valve means for controlling the venting of gas from said pump chamber, a liquid discharge for said pump chamber, a plunger arranged to work in said pump chamber, the latter being provided with a desired clearance and said plunger being adapted to displace liquid through said discharge, packing for said plunger, means for supercharging the clearance space in said pump chamber, a third valve means controlling communication between said supercharging means and said pump chamber, and correlated means for actuating said plunger and said second and third valve means.

6. Apparatus for pumping a volatile liquid having a boiling point temperature materially less than 273° K. at atmospheric pressure, comprising a pump chamber, valve means for controlling the admission of liquid to said pump chamber, a second valve means for controlling the venting of gas from said pump chamber, a liquid discharge for said pump chamber, a plunger arranged to work in said pump chamber, the latter being provided with a desired clearance and said plunger being adapted to displace liquid through said discharge from said chamber, a coil in said discharge arranged to be in heat exchanging relation with a portion of said pump, means for supercharging the clearance space in said pump chamber with gas at elevated pressure when a suction stroke is completed, a gas pump for elevating the pressure of said gas, a packing for said plunger, means for heating said packing, and correlated means for actuating said plunger, all of said valve means and said gas pump.

7. Apparatus for pumping a volatile liquid having a boiling point temperature materially less than 273° K. at atmospheric pressure, comprising a pump chamber having suitable intake and discharge conduits, a reciprocable pumping element operable in said chamber having a portion extending through one end of said chamber, packing means for said portion, heating means associated with said packing means to maintain it within a desired operating temperature range, and means for leading the discharge from said chamber in a heat exchanging relation with the pump between said heating means and the pump chamber.

8. Apparatus for pumping a volatile liquid having a boiling point temperature materially less than 273° K. at atmospheric pressure, comprising the combination of a pump having a pump chamber, a liquid discharge for said chamber, a plunger arranged to work in said pump chamber and having a desired clearance and arranged

to reciprocate in said pump chamber and effect the discharge of liquid, valve means controlling the communication between said pump chamber and the source of supply, said pump parts being adapted to be cooled by the evaporation of a portion of said liquid when introduced into said pump chamber, a gas pump for positively removing said vapors during the suction stroke of said plunger, a second valve means controlling the communication between said gas pump and said pump chamber, and prime moving means connected to actuate said plunger and said second valve means in synchronism and in desired phases.

9. Apparatus for transferring volatile liquids comprising a reciprocating type pump, inlet and discharge connections therefor, a closed chamber independently connected to the interior of said pump, valve means for controlling each of said connections, and means for operating said valve means in timed relation with the operation of said pump to permit passage of material into said chamber from said pump and from said chamber into said pump at predetermined times in the cycle.

10. Apparatus for pumping a volatile liquid having a boiling point temperature materially less than 273° K. at atmospheric pressure, comprising a pump chamber, a reciprocable plunger operable through an opening in one end of said chamber, the latter being constructed to provide an appreciable clearance between said plunger and the inner walls of said chamber, a valve-controlled liquid inlet at the end of said chamber opposite to said opening, a valve controlled passage for liquid discharge, and a valve controlled passage for gas, both said passages having their communication with said chamber spaced a considerable distance from said inlet toward the end having said plunger opening.

11. Apparatus for pumping a volatile liquid having a boiling point temperature materially less than 273° K. at atmospheric pressure comprising the combination of a pump chamber, a reciprocable plunger operable through an opening in one end of said chamber, a valve controlled liquid inlet near the end of said chamber opposite to said opening, a valve controlled passage for liquid discharge, fluid venting means spaced a considerable distance from said inlet toward the end having said plunger opening, and packing means for the portion of the plunger passing through said opening; at least that portion of the plunger coming into contact with the volatile liquid being hollow and having a relatively thin external wall of a metal having a relatively low heat conductivity.

12. Pumping apparatus according to claim 11 in which the hollow of said plunger is filled with a wall supporting material having a lower heat conductivity than said metal.

13. Apparatus for pumping a volatile liquefied gas material having a boiling point temperature materially less than 273° K. at atmospheric pressure, comprising a source of supply of such liquid, a pump chamber, a reciprocatory element operable in said chamber, means for introducing liquid from said source into said chamber during the suction stroke, and means for injecting an additional quantity of said gas material into said chamber preliminary to the discharge stroke at a pressure higher than that afforded by said source to supercharge the pump.

14. Apparatus for pumping a volatile liquid having a boiling point temperature materially less than 273° K. at atmospheric pressure, comprising

ing a pumping chamber provided with a reciprocatory element, means for operating said element, inlet and outlet valves for said chamber, a source of supply of such liquid connected to said chamber through said inlet valve, means for removing a substantial portion of the vapor initially formed upon entry of liquid into said chamber and for subsequently reintroducing said vapor prior to the discharge event in the pump cycle to supercharge the pump.

15. Apparatus for pumping a volatile liquefied gas material having a boiling point temperature materially less than 273° K. at atmospheric pressure, comprising a source of supply of such liquid, a pump chamber, a reciprocatory element operable in said chamber, means for introducing liquid from said source into said chamber during the suction stroke, and auxiliary means operative to remove gas material from said chamber after the pump discharge stroke and to reintroduce it into said chamber prior to the next discharge stroke to supplement the charge from said source and at a higher pressure than that afforded by said source to supercharge the pump.

16. Apparatus for delivering under pressure a liquefied gas material having a boiling point temperature at atmospheric pressure considerably below 273° K. comprising a source of supply of such liquid, a pump chamber connected thereto having a reciprocatory element operable in said chamber, means for introducing liquid from said source into said chamber during the suction stroke, and positively operated suction means for removing from said chamber prior to the delivery stroke of said plunger a substantial portion of the vapor generated therein during said introduction.

17. Apparatus for delivering under pressure to a receiving means a liquefied gas material having a boiling point temperature at atmospheric pressure considerably below 273° K. comprising a source of supply of such liquid, a pump chamber connected thereto having a reciprocatory plunger operable in said chamber, the latter being constructed to provide a clearance space, means for introducing liquid from said source into said chamber during the suction stroke, means for removing from said chamber a substantial portion of the vapor generated therein during said introduction prior to the delivery stroke of said plunger, and means operable following the delivery stroke of said plunger and prior to the introduction of liquid into said chamber for withdrawing a portion of the residual gas material in said chamber into a space having a pressure below that of said receiving means.

18. Apparatus for delivering under pressure a liquefied gas material having a boiling point temperature at atmospheric pressure considerably below 273° K. comprising a source of supply of such liquid, a pump chamber connected thereto having a reciprocatory element operable in said chamber, means for introducing liquid from said source into said chamber during the suction stroke, a receiving means into which the liquid is discharged under elevated pressure during the delivery stroke of said element, and means operable following the delivery stroke and prior to the introduction of liquid into said chamber for withdrawing a portion of the residual gas material in said chamber into a space having a pressure below that of said receiving means.

19. The method of pumping a volatile liquid having a boiling point temperature materially below 273° K. at atmospheric pressure, which

comprises introducing a charge of such liquid from a source thereof into a confined space, effecting a positive displacement of the major part of the introduced liquid from said confined space against a higher pressure, at a predetermined time immediately following such displacement momentarily reducing the pressure in said confined space by release of gas material therefrom into a space at a pressure lower than said higher pressure, and readmitting said released gas material to said confined space at a desired instant prior to the displacement of the next charge therefrom.

20. The method of pumping a volatile liquid material having a boiling point temperature below 273° K. at atmospheric pressure which comprises maintaining a supply of the liquid to be pumped in a state corresponding substantially to its equilibrium boiling temperature at the supply pressure, introducing a charge of liquid therefrom into a confined space at a pressure not materially different from said supply pressure, supercharging said confined space by adding an additional quantity of the gas material, and effecting a positive displacement of the major part of the gas material from said confined space against a higher pressure.

21. The method of pumping a volatile liquid material having a boiling point temperature below 273° K. at atmospheric pressure which comprises maintaining a supply of the liquid to be pumped in a state corresponding substantially to its equilibrium boiling point temperature at the supply pressure, introducing a charge of liquid therefrom into a confined space at a pressure not materially different from said supply pressure, effecting positive displacement of the major part of the gas material from said confined space to an area at a desired relatively high pressure, and independently releasing a minor portion of said gas material from a point of said confined space at an appreciable distance from the point of introduction of said charge to an area of lower pressure.

22. The method of pumping a volatile liquid material having a boiling point temperature below 273° K. at atmospheric pressure which comprises maintaining a supply of the liquid to be pumped in a state corresponding substantially to its equilibrium boiling point temperature at the supply pressure, introducing a charge of liquid therefrom into a confined space at a pressure not materially different from said supply pressure, effecting positive displacement of the major part of the gas material from said confined space to an area at a desired relatively high pressure, independently releasing a minor portion of said gas material from a point of said confined space at an appreciable distance from the point of introduction of said charge to an area of lower pressure, and collecting and reintroducing said released minor portion into said confined space.

23. A pump for highly volatile liquids comprising intake and discharge valves, a pump body having a cylindrical opening and a plunger reciprocating therein, the diameter of said plunger being materially less than the internal diameter of said opening, packing surrounding said plunger within said body, a working barrel in said body adjacent said valves in alignment with said opening; said packing being widely spaced from said working barrel to provide a longitudinally extended annular open space between said plunger and said cylindrical opening, the construction be-

ing adapted to permit a restricted flow of the material being pumped between said working barrel and said annular space, and means for refrigerating at least a portion of said pump body surrounding said annular space.

24. Apparatus for pumping a volatile liquid having a boiling point temperature materially less than 273° K. at atmospheric pressure, comprising a pump chamber, a reciprocable plunger operable through an opening in one end of said chamber the latter being constructed to provide an appreciable clearance between said plunger and the inner walls of said chamber, a valve-controlled liquid inlet at the end of said chamber opposite to said opening, a valve-controlled passage for liquid discharge, packing means for the portion of the plunger passing through said opening, and restricted means for venting gas material from the pump chamber at a point an appreciable distance from the inlet toward said opening whereby heated gas material may be removed.

25. Apparatus for pumping a volatile liquid having a boiling point temperature materially less than 273° K. at atmospheric pressure, comprising a pump chamber, a reciprocable plunger operable through an opening in one end of said chamber, a valve-controlled liquid inlet at the end of said chamber opposite to said opening, a valve-controlled passage for liquid discharge, packing means for the portion of the plunger passing through said opening, and restricted means for venting gas material from the pump chamber at a point an appreciable distance from the inlet toward said opening; a fluid chamber extending around the working portion of said pump chamber arranged to supply liquid to said liquid inlet; and means providing communication between said venting means and said fluid chamber.

26. Apparatus for pumping a volatile liquid having a boiling point temperature materially less than 273° K. at atmospheric pressure, comprising the combination with a container for supplying liquid to be pumped, of a pump having a pump chamber and a surrounding fore chamber connected to said container and to said pump chamber, valve means for controlling the admission of liquid to said pump chamber from said fore chamber, a liquid discharge conduit from said pump chamber, a pumping element arranged to work in said pump chamber to displace liquid through said discharge conduit, the connections between said container and fore chamber including a liquid conduit connected between the liquid space of said container and the fore chamber for feeding liquid to the latter and a vapor conduit from the upper portion of said fore chamber to said container to permit the release of vapor to said container, and liquid level response means constructed and arranged to prevent flow of liquid through said vapor conduit to said container.

27. Pumping apparatus according to claim 26 in which said pumping element enters through one end of said pump chamber and said inlet is adjacent the other end of said pump chamber, there being a packing seal between the pumping element and said one end of the pump chamber, a restricted vent from said pump chamber at a point intermediate between said ends, and means providing communication between said vent and said vapor conduit.

28. Apparatus for pumping a volatile liquid having a boiling point temperature materially

less than 273° K. at atmospheric pressure, comprising the combination with a container for supplying liquid to be pumped, of a pump having a pump chamber with a warm end, a cold end, and a surrounding fore chamber, the cold end being within said fore chamber, a liquid conduit connecting the liquid space of said container and said fore chamber for supplying liquid to the fore chamber, a vapor conduit connecting an upper portion of said fore chamber with said container for venting vapor to said container, a valved inlet between the cold end of the pump chamber and said fore chamber, a valved discharge from said pump chamber, a pumping element arranged to work in said pump chamber and displace liquid through said discharge, and a vent from said pump chamber at a point intermediate between said cold and warm ends and spaced from said inlet toward said warm end.

29. Apparatus for pumping a volatile liquid having a boiling point temperature materially less than 273° K. at atmospheric pressure comprising the combination of a pump chamber, a reciprocable plunger operable through an opening in one end of said chamber, a valve-controlled liquid inlet near the end of said chamber opposite to said opening, a valved discharge from said pump chamber, said chamber having a working barrel portion in which the end of said plunger reciprocates to displace liquid through said discharge, said working barrel portion having a diameter larger than said plunger to provide a desired clearance, a clearance space between the plunger and the pump chamber in the end of said chamber adjacent said opening for trapping gas material outwardly of said working barrel portion, a packing seal between the plunger and the pump chamber located outwardly of said clearance space, and means extending around said pumping chamber in the region of said clearance space for removing heat therefrom.

30. Apparatus for pumping a highly volatile liquid having a boiling point temperature materially less than 273° K. at atmospheric pressure, comprising a pump body having a working chamber therein, a reciprocable plunger extending through an opening in said pump body and having an inner end portion operable in said working chamber, the latter being constructed to provide a substantial clearance between said plunger and the inner wall of said chamber, a valve controlled liquid inlet at the end of said chamber opposite to said opening, a valve controlled passage for liquid discharge, packing means for the portion of the plunger passing through said opening, said packing means being widely spaced from said working chamber the intervening space comprising an elongated opening through which said plunger extends of a diameter to provide an annular fluid space of substantial radial thickness about said plunger, said annular space having sufficient communication with said working chamber to allow entrance of fluid therefrom, and means for cooling at least a portion of said pump body surrounding said annular space embodying a fluid passage extending around said portion and means for passing a cold fluid through said passage means.

31. Apparatus for pumping a highly volatile liquid having a boiling point temperature materially less than 273° K. at atmospheric pressure, comprising a pump body having a working chamber therein, a reciprocable plunger extending through an opening in said pump body and having an inner end portion operable in said working

chamber, the latter being constructed to provide a substantial clearance between said plunger and the inner wall of said chamber, a valve controlled liquid inlet at the end of said chamber opposite to said opening, a valve controlled passage for liquid discharge, packing means for the portion of the plunger passing through said opening, said packing means being widely spaced from said working chamber the intervening space comprising an elongated opening through which said plunger extends of a diameter to provide an annular fluid space of substantial radial thickness about said plunger, said annular space having sufficient communication with said working chamber to allow entrance of fluid therefrom, and restricted means for venting gas material from the pump body at a point spaced from said inlet toward the opposite end of said pump body.

32. A pump for liquefied gases comprising a pump body including a working barrel portion, a plunger of less diameter than said barrel reciprocating therein, a packing element surrounding said plunger, and means for removing heat from said plunger, said means comprising a jacket surrounding the pumping end of said pump, and means for passing a fluid at low subatmospheric temperature through said jacket, said pump body including an elongated portion interposed between said working barrel portion and said packing and having an internal diameter larger than that of the plunger to form an enclosure of space around said plunger, said space being in sufficient communication with said working barrel to permit passage of the pumped fluid thereinto.

33. Apparatus for pumping a volatile liquid having a boiling point temperature materially less than 273° K. at atmospheric pressure, comprising the combination with a container for supplying liquid to be pumped, of a pump having a pumping chamber and a plunger operable therein, said pump having a cold end including said pumping chamber and an outer warm end including means connected to operate said plunger, a surrounding fore chamber, the cold end being within said fore chamber and located at a level below said warm end, a liquid conduit connecting the liquid space of said container and said fore chamber for supplying liquid to the latter, a vapor conduit connecting an upper portion of said fore chamber

with said container for venting vapor to said container, a valved inlet between said fore chamber and the inner end of the pumping chamber opposite the said warm end, a valved discharge from said pumping chamber, and means for venting gas into said fore chamber from the end of said pumping chamber opposite to and spaced from said valved inlet.

34. Apparatus for pumping a liquefied gas having a boiling point temperature materially less than 273° K. at atmospheric pressure comprising the combination with a container for holding and supplying liquefied gas to be pumped, of a pump having a pump chamber, a surrounding fore-chamber holding a body of the liquefied gas in which the pump chamber is immersed, means for the admission of liquid charges to said pump chamber from said forechamber, a liquid discharge conduit from said pump chamber, and a pumping element arranged to work in said pump chamber to displace liquid through said discharge conduit, at least the liquefied gas body holding portion of said forechamber being lower than said container; a liquid conduit connected between the liquid space of said container and the fore-chamber for feeding liquid to the latter; a vapor conduit from the upper portion of said fore-chamber for the release therefrom of excess vapor tending to prevent the rise of liquid in the fore-chamber to a predetermined liquid level; and liquid level response means associated with said vapor conduit for preventing flow of liquefied gas through said vapor conduit.
